(57) **CLAIM**

The ornamental design for a “frame support swivel bracket”, as shown and described.

DESCRIPTION

FIG. 1 is an environmental perspective view of a frame support swivel bracket showing my new design; FIG. 2 is an enlarged perspective view of one item according to the design shown in FIG. 1; FIG. 3 is an enlarged perspective view of the design of FIG. 2 shown rotated 180° around the centerline of its base; FIG. 4 is a front view of the design of FIG. 2; FIG. 5 is a right side view of FIG. 2; FIG. 6 is a back view of FIG. 2; FIG. 7 is a left side view of FIG. 2; FIG. 8 is a bottom view of FIG. 2, the top view being a mirror image thereof; and, FIG. 9 is a another environmental perspective view thereof. FIG. 10 is a reduced, environmental right side elevational view.

The broken lines showing oval and square frames and an additional bracket are for illustrative purposes only and no part of the claimed design.
